UNITED STATES PATENT OFFICE.

JOHN F. MCKAY AND DAVID J. MCKAY, OF BOWIE, LOUISIANA.

OVERHEAD-CONVEYER SYSTEM.

No. 798,822.

Specification of Letters Patent.

Patented Sept. 5, 1905.

Application filed January 13, 1905. Serial No. 240,900.

To all whom it may concern:

Be it known that we, JOHN F. MCKAY and DAVID J. MCKAY, citizens of the United States, and residents of Bowie, in the parish of Lafourche and State of Louisiana, have invented a new and Improved Overhead-Conveyer System, of which the following is a full, clear, and exact description.

Our invention relates to certain improvements in overhead cableways or conveyers, especially those intended for conveying or "skidding" logs. These apparatus are generally provided with a main or track cable on which a carriage runs, this carriage being provided with an outhaul-line and with a skidding-line, one end of which is attached to the hoisting-engine and the other end after running through a block on the carriage is provided with means for engaging the logs. Difficulty has been experienced in drawing out this skidding-line at the end of the outhauling movement of the carriage, and our present invention contemplates a novel means for drawing or paying out the skidding-line after this outward movement of the carriage and preparatory to loading or reloading the same.

Our invention also contemplates an improved loading-carriage which is employed in connection with one of the guides for the main cable and which serves to permit loading the logs on a wagon, railway-car, or other vehicle.

The invention also contemplates an improved tension-block which is employed in connection with devices for maintaining the main or track cable at the proper tension, and, finally, we have provided an improved double-block structure, attached to the carriage and accommodating the skidding-line outhaul and also a peculiar detachable section for the skidding-line, which detachable section greatly facilitates the loading of the conveyer, all of which will be made fully to appear hereinafter.

Reference is had to the accompanying drawings, which illustrate as an example the preferred embodiment of our invention, in which drawings like characters of reference indicate like parts throughout the views, and in which—

50 Figure 1 is a general view of a cableway for skidding logs and embodying our improvements. Fig. 2 is a side elevation of a peculiar double block which is applied to the carriage to accommodate the skidding-line and the skidding-line outhaul. Fig. 3 is a section of said block on the line 33 of Fig. 2. Fig. 4 is

a section on the line 44 of Fig. 2. Fig. 5 is a side elevation of one of the blocks employed in connection with the tension-line for the main cable. Fig. 6 is a section thereof on the line 66 of Fig. 5. Fig. 7 is an end view of this block shown in Figs. 5 and 6. Fig. 8 is a side elevation of the novel loading-carriage. Fig. 9 is a plan view of the same, and Fig. 10 is an end elevation looking in the direction of the arrow 10 in Fig. 8.

12 indicates a main cable which is attached to and supported by what are commonly known as the "head-tree" 14 and "tail-tree" 15. Cableways of the type to which our invention relates are usually erected in the forest, and trees are employed for the cable-support, although it is obvious that especially-erected poles or any other such means could be employed. The main cable 12 is attached in any suitable manner to the tail-tree 15, and it is connected to the head-tree 14 through the medium of a tension-line 16 and tension-line blocks 17. This tension-line is rove over the blocks 17 down to a tension-drum 18 in essentially the manner set forth in our prior patent for tension-regulators for overhead cables, No. 757,952, dated April 19, 1904.

19 indicates a guy or guys for the tail-tree, 85 and 20 indicates a guy for the head-tree.

The blocks 17 are of the peculiar construction illustrated in Figs. 5, 6, and 7. This structure comprises a shell formed of an integral casting and comprising cheeks 17^a, 90 connected at their outer ends by a web 17^b and joined at their inner ends by a head 17^c, having an orifice 17^d therein. 17^e indicates a sheave which is carried on a pin 17^f, the pin passing through the shell, as usual, and having an oil-groove 17^g therein. This groove communicates with oil-pockets 17^h, formed in the shell of the block and having oil-feeding orifices leading to the outer surfaces thereof, as shown. The block is attached to its support or to the main cable, as the case may be, by passing the strap or pennant or the bight of the main cable into the cavity 17ⁱ and around a pin 17^j. This pin is connected to the shell of the block by a chain 17^k and is held in place by a linchpin 17^l, also connected to the shell by a chain 17^m.

21 indicates the skidding-carriage, which may be of any desired form and which acts on the main cable 12 in the usual manner.

22 indicates an outhaul-line which is attached to the carriage and rove over a block

23, attached to the tail-tree 15, thence back to guide-sheaves 24, attached to the carriage 21, and over a block 25, attached to the head-tree 14, and thence down to a drum 26 of the 5 hoisting-engine. By hauling in on this line 22 its lower run will be drawn outward, and with it the skidding-carriage 21 will move toward the tail-tree.

27 indicates the skidding-line, which passes 10 from a drum 28 of the hoisting-engine upward over a block 29 on the head-tree 14. At the point 30 the skidding-line is provided with an eye, and this eye is adapted to be engaged by sister hooks joined by a chain or 15 otherwise to the end section 27^a of the skidding-line. This end section passes through a double block 31, around the lower sheave thereof, and thence descends to the ground, it being provided at its lower end with a 20 means 32 for engaging it with a log or logs. In the ordinary operation of these apparatus when the skidding-line is engaged with the log it is hauled in, bringing with it not only the log, but the carriage 21 and its attachments. 25 As the carriage is hauled out by the line 22 the log-engaging means jam in the block 31, and the skidding-line is hauled out with the carriage. At the end of this outhauling movement it is necessary to further haul the skid- 30 ding-line, so as to drop the means 32 to the ground. For this purpose we provide a skidding-line outhaul 33, which is wound around the drum 34 of the hoisting-engine and passes up therefrom over a block 35, attached to the 35 head-tree. From this point the skidding-line outhaul 33 passes around the upper sheave of the double block 31, and thence back toward the head-tree and is spliced into or otherwise joined to the skidding-line 27 at the joint 36. 40 Now therefore after the operation of outhauling the skidding-carriage 21 and line 27 the drum 34 should be operated, causing the outhaul 33 to exert on the skidding-line a further outhauling strain, drawing said line 45 through the block 31 and dropping the tongs 32 or other log-attaching means to the ground, so that the tongs may be conveniently engaged with the logs.

The peculiar double block 31 is illustrated 50 in Figs. 2, 3, and 4. Said block comprises a cast-metal shell having cheek-pieces 31^a, connected by webs 31^b, as shown. These parts may be integral or otherwise and provided with stay-bolts 31^c, as illustrated. 31^d indicates a becket, which is swiveled onto the upper end of the block, as shown. The upper sheave 31^e is mounted on a pin 31^f and fits snugly between the cheek-pieces, and the lower sheave 31^g is mounted on a pin 31^h. Between these two sheaves the cheek-pieces are spread apart to form an enlarged space 31ⁱ, which permits the sister hooks and chain on the upper end of the skidding-line end section 27^a to be moved freely through the shell 65 of the block. In the operation of the appa-

ratus a plurality of these end sections 27^a are provided, and while one is being employed to track or skid the logs toward the head-tree the workmen toward the tail-tree may be engaged in fastening another of said end sections 27^a to another group of logs, so that when the skidding-carriage is returned for another load they have only to disengage the end section 27^a first employed and reengage the sister hooks and chain of the second end 70 section with the skidding-line, thus saving much time in loading the conveyer. The peculiar form of the double block, particularly the enlarged opening 31ⁱ above the sheave 31^g, greatly facilitates this operation. 80

The loading-carriage is mounted on the guy 20 of the head-tree 14 (see Fig. 1) and comprises a body 37, bearing on the guy. 38 indicates a sheave adapted to run on the guy, and 39 a shell facilitating the connection with the carriage of a block 40, over which a loading-line 41 is rove. Said line is provided in one end with tongs 42 or other means for attaching the logs, and after passing the block 40 the loading-line is rove over a block 43, 90 and thence passes down to a drum 44 of the hoisting-engine. By this gear the logs may be hoisted onto the railway-car or other vehicle intended for the transportation of the timber. 95

The novel form of our loading-carriage is illustrated in Figs. 8, 9, and 10. The body 37 is formed with a groove 37^a on its under side, which fits it snugly to the guy 20. U-bolts 37^b are engaged with the body and pass around the under side of the guy to clamp the body firmly to the guy. At its upper end the body is formed with a fork 37^c, carrying a pin 37^d. On this pin the sheave 38 is mounted. The shell 39 comprises two cheek-pieces 39^a, hung 100 at their upper ends on the pin 37^b and connected at their lower end with a pin 39^b. With this pin the block 40 is engaged in any suitable manner. The sheave 38 bears the weight of the log during the loading operation and 105 also permits the carriage to be run freely over the guy during the operation of adjusting the carriage, for which purpose the U-bolts 37^b are slackened. After the carriage is properly adjusted it is clamped fast by the U-bolts. 115

Having thus described the preferred form of our invention, what we claim as new, and desire to secure by Letters Patent, is—

1. In a cableway, the combination with head and tail trees or supports, of a main cable attached to the tail-tree, a tension-line and winding means, sheaves for the tension-line, said sheaves and tension-line connecting the main cable with the head-tree, guys for the head and tail trees, a loading-carriage mounted to 120 run on the head-tree guy, a loading-line engaged with the loading-carriage, a skidding-carriage, an outhaul-line therefor, a skidding-line, a double block on the skidding-carriage over one sheave on which the skidding-line 125

- runs, and a skidding-line outhaul running over the other sheave of the double block.
2. In a cableway, the combination with head and tail trees or supports, of a main cable attached to the tail-tree, a tension-line and winding means, sheaves for the tension-line, said sheaves and tension-line connecting the main cable with the head-tree, guys for the head and tail trees, a loading-carriage mounted to run on the head-tree guy, a loading-line engaged with the loading-carriage, a skidding-carriage, an outhaul-line therefor, a skidding-line, a double block on the skidding-carriage over one sheave on which the skidding-line runs, and a skidding-line outhaul running over the other sheave of the double block, said skidding-line outhaul being joined at one end to the skidding-line and having its other end adapted to have a hauling force exerted thereon.
3. In a cableway, the combination with head and tail trees or supports, of a main cable attached to the tail-tree, a tension-line and winding means, sheaves for the tension-line, said sheaves and tension-line connecting the main cable with the head-tree, guys for the head and tail trees, a loading-carriage mounted to run on the head-tree guy, a loading-line engaged with the loading-carriage, a skidding-carriage, an outhaul-line therefor, a skidding-line, a double block on the skidding-carriage over one sheave on which the skidding-line runs, and a skidding-line outhaul running over the other sheave of the double block, the said skidding-line being formed in two parts releasably connected together for the purpose specified.
4. In a cableway, the combination of a main cable, a carriage adapted to run theron, a carriage-outhaul, a double block supported from the carriage, a skidding-line running over one sheave of the block, and a skidding-line outhaul having one end joined to the skidding-line, said outhaul being rove over the other sheave of the double block.
5. A skidding-conveyer having a skidding-line formed in two sections, with a releasable connection between them for the purpose specified.
6. In a skidding-conveyer, the combination with a skidding-carriage, of a block thereon, said block having a shell and a sheave, the shell having an enlarged opening above the sheave, and a skidding-line adapted to run on said sheave and formed in two sections with a releasable connection between them, the said enlarged opening in the shell of the block permitting the movement of said connection through the block.
7. A double block for cableways comprising a shell and two sheaves mounted thereon at different points along the length of the shell, and the shell having an enlarged opening between the sheaves, for the purpose specified.
8. A double block for cableways, comprising

an elongated shell, and a sheave mounted in each end portion thereof, the said shell having an enlarged opening between the sheaves, for the purpose specified.

9. A double block for cableways, comprising an elongated shell, and a sheave mounted in each end portion of the shell, the cheek-pieces of the shell at a point between the sheaves being bulged outward from each other, to form an enlarged opening between the sheaves, for the purpose specified.

10. In a cableway, the combination with a tree or support and its guy, of a loading-carriage body bearing on the guy, a sheave connected with the body and bearing on said guy, a hoisting-gear, and means for throwing the load of said gear upon the sheave.

11. In a cableway, the combination with a tree or support and its guy, of a loading-carriage body arranged to bear theron, a sheave bearing on the guy, a pin connecting the sheave with the body, and a shell adapted to bear the load of the carriage and hung from the said pin.

12. A cableway-carriage, comprising a body adapted to bear on the cable, a sheave connected with the body and also bearing on the cable, and means for placing the load of the carriage on the sheave.

13. A cableway-carriage, comprising a body adapted to bear on the cable, a sheave also bearing on the cable, a pin connecting the sheave with the body, and means for exerting a load on said pin.

14. A cableway-carriage, comprising a body adapted to bear on the cable, a sheave also bearing on the cable, a pin connecting the sheave with the slide, and a shell hung from the pin and adapted to bear a load exerted thereon.

15. A cableway-carriage, comprising a body having a groove to receive the cable, a U-bolt embracing the cable and attached to the body to clamp the body to the cable, a sheave engaging the cable and connected with the body, and means for exerting a load on the carriage.

16. A cableway, comprising a body having a groove in its under side to receive the cable, a U-bolt fastened to the body and embracing the cable, to clamp the body in place, a sheave adapted to bear on the cable, a pin connecting the sheave with the slide, and a means for exerting a load on said pin.

17. A cableway-carriage, comprising a body having a groove to receive the cable, a U-bolt attached to the body and embracing the cable, a sheave bearing on the cable, a pin connecting the sheave with the body, and a shell hung from the pin and adapted to have the load exerted thereon.

18. In a cableway, the combination of a main cable, a carriage adapted to run thereon, a carriage-outhaul for moving the carriage on the main cable in one direction, a skidding-line for moving the carriage on the cableway

in the other direction, the skidding-line being formed in two sections with a releasable connection between them, a hauling means with which the outhaul and skidding-line are connected, and a skidding-line outhaul actuated by said hauling means and joined to the skidding-line at the section thereof adjacent to the hauling means.

19. In a cableway, the combination of a main cable, a carriage adapted to run thereon, a carriage-outhaul adapted to move the carriage on the main cable in one direction, a skidding-line adapted to move the carriage on the main cable in the other direction, the skidding-line being formed in two sections with a releasable connection between them, a hauling means with which the carriage-outhaul and skidding-line are connected, a sheave supported by the carriage, and a skidding-line outhaul in connection with said hauling means and rove over said sheave, and connected with the skidding-line section adjacent to the hauling means.

20. In a cableway, the combination of a main cable, a carriage adapted to run thereon, a carriage-outhaul, a double block supported on the carriage, a skidding-line rove over one sheave of said block and formed in two sec-

tions with a removable connection between said sections, a hauling means with which the outhaul and skidding-line are connected, and a skidding-line outhaul actuated by the hauling means and rove over the second sheave of the double block and connected to the skidding-line at the section adjacent to said hauling means.

21. In a cableway, the combination of a main cable, a carriage adapted to run thereon, means for moving the carriage on the cable in one direction, a double block attached to the carriage, a skidding-line rove over one sheave of the block, and a skidding-outhaul rove over the other sheave of the double block.

In testimony whereof we have signed our names to this specification in the presence of two subscribing witnesses.
